UNITED STATES PATENT OFFICE.

EDMUND BRUDER, OF CHICAGO, ILLINOIS, ASSIGNOR TO HAROLD I. KOPPELMAN, OF WILMETTE, ILLINOIS.

DISPENSER.

1,411,477.

Specification of Letters Patent.

Patented Apr. 4, 1922.

Application filed January 29, 1918. Serial No. 214,286.

To all whom it may concern:

Be it known that I, EDMUND BRUDER, a citizen of the United States, residing at Chicago, in the county of Cook and State of Illinois, have invented certain new and useful Improvements in Dispensers, of which the following is a specification.

This invention relates to devices of the class typified by liquid soap dispensers, the objects of the invention being to produce a dispenser which shall not be liable to get out of order, nor be readily tampered with, and which shall effectively prevent dripping when the valve is closed.

In the accompanying drawings, Figure 1 is a fragmental sectional view of a dispenser embodying the features of my invention. Fig. 2 is a sectional view taken in the plane of dotted lines 2—2 of Fig. 1. Figs. 3 and 4 are fragmental side views of the body of the dispenser. Fig. 5 is a sectional view taken in the plane of dotted line 5—5 of Fig. 2. Fig. 6 is a section on line 6—6 of Fig. 5. Fig. 7 is an inner side view of the rotatable valve member. Fig. 8 is a section on dotted line 8—8 of Fig. 3.

The embodiment herein shown of the invention comprises a bracket 1 which may be of any suitable form and having any preferred means for attaching the bracket to a wall or other suitable support. Integral with the forward end of the bracket 1 is a socket 2 in which is secured the lower end of a container 3. Below the socket 2 is located the body 4 of the dispenser. In one end of the body 4 is formed an axial chamber 5 that contains an oscillatory valve member for controlling the flow of soap. In the opposite end of the body 4 is provided a chamber 6, one half of the chamber being formed of a recess in the body 4 and the other half being formed of a recess in a plug 7 that is screwed into an axial internally-threaded socket 8 in the body. The chamber 6 is provided with an elastic diaphragm or wall 9 which may consist of a sheet of rubber, said sheet being herein shown as secured in place by having its margin clamped between the inner end wall of the recess 8 and the inner side of the plug 7. The space in the chamber 6 at the outside of the diaphragm 9 communicates with the atmosphere by means of one or more ports 10.

An axial port 11 extends from the space

within the chamber 6 at the inner side of the diaphragm 9 to the inner end wall of the chamber 5. 12 is a supply duct leading downward from the socket 2 and opening upon the inner end wall of the chamber 5. 60 A discharge duct 13 extends from the inner end wall of the chamber 5 to a discharge nozzle 14. The function of the valve member hereinbefore mentioned is to connect the chamber 6 alternately with the ducts 12 and 13. Said valve member is indicated at 15 and consists of a disk fitting within the chamber 5 in contact with the inner end wall of said chamber. In the inner face of the valve member 15 is a groove 16 extending 70 from the axis of the valve member to a point adapted to register with the lower end of the supply duct 12 or the upper end of the outlet duct 13, depending upon the position of the valve member.

The means for oscillating the valve member 15 comprises a lever having the general form of a bail and comprising two arms 17 and 18 and a connecting portion or cross-piece 19. For convenience in manufacture, 80 one half of the crosspiece 19 may be formed integral with each of said arms. Herein is shown a dowel pin 20 assisting to connect the two halves of said crosspiece. The upper ends of the arms 17 and 18 fit pivotally 85 within the outer ends of the chamber 5 and the recess 8, respectively. 21 is a duct extending through the pivot portion of the arm 18 to permit atmospheric pressure to be exerted upon the diaphragm 9 through the 90 ports 10. The arms 17 and 18 are rigidly connected together by means of a screw 22. The head 23 of the screw 22 is preferably concealed by countersinking the head in the arm 17 and filling the countersink flush with 95 the surface of the arm 17 with a substance adapted to be nickel-plated together with the remained of the arm.

The means for connecting the valve member 15 to the lever comprises a tongue 24 (Fig. 100 2) formed integral with the pivot portion of the arm 17 and extending inwardly therefrom, said tongue fitting into a slot or groove 25. (Fig. 3) formed in the stem 26 of the valve member 15.

The means for pressing the valve member 15 against its seat, i. e., the inner end wall of the chamber 5, to prevent leakage of soap, and for normally holding the valve member 110 in closed position, comprises a coiled tor-

sion and expansion spring 27 (Fig. 2) secured at one end to the valve member 15 and at its other end to a disk 28 having a hub 29 in which the stem 26 is rotatably mounted. The disk 28 is rigidly secured within the chamber 5 in any suitable manner. Herein the disk is shown as provided with two diametrically opposite notches 30 to receive studs 31 projecting inwardly from the 10 wall of the chamber 5. The disk 28 is provided with two diametrically opposite notches 32 adapted to pass the studs 31, so that the disk 28 may be inserted into the chamber 5 with the notches 32 in register 15 with the studs 31. After the disk has been inserted beyond the studs 31, it may be turned to bring the notches 30 into register with said studs. The spring 27 holds the disk 28 pressed against the studs 31.

20 The parts normally occupy the position shown in Figs. 1 and 2 and the full-line position shown in Fig. 5. The chamber 6 is then in communication with the interior of the container 3 through the supply duct 12, the groove 16 and the port 11, as shown in Figs. 5 and 6. The weight of the soap will distend the diaphragm 9 into the position shown in dotted lines in Fig. 2. When it is desired to discharge soap, the user 30 presses his hand against the crosspiece, thereby swinging said crosspiece rearwardly and upwardly into the position shown in dotted lines in Fig. 5 and bringing the hand of the user beneath the discharge nozzle 14.

35 The valve 15 is thereby turned to carry the groove 16 out of register with the supply duct 12 (thus cutting off communication between the container 3 and the chamber 6), and bringing the groove 16 into communication 40 with the discharge duct 13. Thereupon soap flows from the chamber 6 through the port 11, the groove 16 and the discharge duct 13 into the hand of the user. When the user withdraws his hand, the spring 27 45 aids gravity in returning the lever and the valve 15 to normal position, thereby interrupting communication between the chamber 6 and the discharge duct 13 and re-establishing communication between the container 3 and the chamber 6.

50

In the present embodiment of the invention, the swinging movements of the lever are limited by contact of the screw 22 with the side of the discharge nozzle 14 and the 55 lower side of the bracket 1, as indicated in Fig. 5, but any other suitable means may be employed for this purpose.

It will be understood that the construction herein shown is applicable also to the 60 dispensing of soda-fountain sirups, the lever being operable in the act of placing a glass or other receptacle beneath the discharge nozzle 14. Other uses will doubtless suggest themselves, and hence the invention is not 65 to be limited to the dispensing of any par-

ticular kind of liquid, nor to the particular construction herein illustrated except to the extent indicated by the appended claims.

In certain of the following claims I have used the term "receptacle" to denote the 70 hand of the user in the case of a soap dispenser, or a drinking glass or the like in the case of a sirup or beverage dispenser.

I claim as my invention:

1. A dispenser comprising a container, a 75 body having an axial chamber, there being a supply duct extending from the container to the inner end wall of said chamber, said body also having a chamber having an elastic wall, the last mentioned chamber having 80 an axial port extending to the inner end wall of the first mentioned chamber, the body also having a discharge duct extending from said inner end wall, an oscillatory valve member mounted in the first mentioned 85 chamber in contact with said inner end wall and having a groove arranged to connect the supply duct and the discharge duct alternately with said axial port, a lever pivoted to the body on the axis of said valve member, a tongue and groove connection between the valve member and said lever, a disk non-rotatably mounted in the first mentioned chamber, and a combination torsion 90 and expansion spring interposed between and secured to the valve member and said disk.

2. A dispenser comprising a container, a body having a chamber, there being a supply duct extending from the container to the inner end wall of said chamber, said body also having a second chamber, the second chamber having a port extending to the inner end wall of the first chamber, the body also having a discharge duct extending from 100 said inner end wall, an oscillatory valve member mounted in the first chamber in contact with said inner end wall and having a groove arranged to connect the supply duct and the discharge duct alternately with said port, a lever pivoted to the body and connected to turn the valve member, a disk non-rotatably mounted in the first chamber, and a combination torsion and expansion spring 105 interposed between and secured to the valve 110 member and said disk.

3. A dispenser comprising a container, a body having a chamber, there being a supply duct extending from the container to the inner end wall of said chamber, said body also having a second chamber, the second chamber having a port extending to the inner end wall of the first chamber, the body also having a discharge duct extending from 120 said inner end wall, an oscillatory valve member mounted in the first chamber in contact with said inner end wall and having a groove arranged to connect the supply duct and the discharge duct alternately with said port, a lever connected to turn the 125 130

valve member, and a combination torsion and expansion spring in the first chamber and arranged to press the valve member against said inner end wall and to turn the 5 valve member and the lever.

4. A dispenser comprising a container, a body having a valve seat and a supply duct extending from the container to the valve seat, said body also having a chamber having an axial port extending to the valve seat, the body also having a discharge duct 10 extending from said valve seat, an oscillatory valve member mounted in contact with said valve seat and having a groove arranged to connect the supply duct and the discharge duct alternately with said axial port, and means for oscillating the valve member.

5. A dispenser comprising a container, a body having an axial chamber, there being a supply duct extending from the container to the inner end wall of said chamber, said body also having an axial recess, a plug 20 screwed into said recess, the body having a port connecting said chamber and recess, the body also having a discharge duct extending from said inner end wall, an oscillatory valve member mounted in said chamber in contact with said inner end wall and having a groove arranged to connect the supply duct and the discharge duct alternately with said port, an arm pivotally mounted in said chamber, an arm pivotally mounted in said recess, said arms being connected together, and a connection between one of 30 said arms and said valve member for turning the valve member when the arms are swung, said arms extending to a point beneath the discharge nozzle and being arranged to swing rearwardly away from the nozzle.

6. A dispenser comprising a container, a body having an axial chamber, there being a supply duct extending from the container to the inner end wall of said chamber, said body also having an axial recess, a plug 45 screwed into said recess, the body having a port connecting said chamber and recess, the body also having a discharge duct extending from said inner end wall, an oscillatory valve member mounted in said chamber in contact with said inner end wall and having a groove arranged to connect the supply duct and the discharge duct alternately with said port, an arm pivotally mounted 50 in said chamber, an arm pivotally mounted in said recess, said arms being connected together, and a connection between one of said arms and said valve member for turning the valve member when the arms are swung.

7. A dispenser comprising a body having an axial chamber, there being a supply duct extending to the inner end wall of said chamber, said body also having an axial

recess, a plug screwed into said recess, the body having a port connecting said chamber and recess, the body also having a discharge duct extending from said inner end wall, an oscillatory valve member mounted in said chamber in contact with said inner end wall 70 and having a groove arranged to connect the supply duct and the discharge duct alternately with said port, an arm pivotally mounted in said chamber, an arm pivotally mounted in said recess, said arms being 75 connected together, and a connection between one of said arms and said valve member for turning the valve member when the arms are swung.

8. A dispenser comprising a body having an axial chamber, there being a supply duct 80 extending to the inner end wall of said chamber, said body also having a second chamber, the body having a port connecting said chambers, the body also having a discharge duct extending from said inner end wall, an oscillatory valve member mounted in the first chamber in contact with said inner end wall and having a groove arranged to connect the supply duct and the discharge duct alternately with said port, an arm pivotally mounted in the first chamber, and a connection between said arm and said valve member for turning the valve member when the arm is swung. 95

9. A dispenser comprising a body having a valve seat and a supply duct extending to the valve seat, said body also having a chamber having an axial port extending to the valve seat, the body also having a discharge duct extending from said valve seat, an oscillatory valve member mounted in contact with said valve seat and having a groove arranged to connect the supply duct and the discharge duct alternately with said axial port, and a part non-rotatably connected to the valve member and extending below the discharge duct into position yielding to obstruct the positioning of a receptacle beneath the discharge opening. 100

10. A dispenser comprising a body having a valve seat and a supply duct extending to the valve seat, said body also having a chamber having a port extending to the valve seat, the body also having a discharge duct extending from said valve seat, a valve member mounted in contact with said valve seat and arranged to connect the supply duct and the discharge duct alternately with said port, and a part connected to move the valve member and extending below the discharge duct into position yielding to obstruct the positioning of a receptacle beneath the discharge opening. 115

In testimony whereof, I have hereunto set my hand.

EDMUND BRUDER.
